MEANS FOR CONTROLLING SPEED OF AND EXPANDING CLOTH

Filed Sept. 24, 1931

UNITED STATES PATENT OFFICE

WILLIAM J. KOCH, OF MIDLAND PARK, NEW JERSEY, ASSIGNOR TO VAN VLAANDEREN MACHINE COMPANY, OF PATERSON, NEW JERSEY, A CORPORATION OF NEW JERSEY

MEANS FOR CONTROLLING SPEED OF AND EXPANDING CLOTH

Application filed September 24, 1931. Serial No. 584,835.

On the delivery of fabric from a tentering machine, or tenter, it frequently is desired to subject it to a drying and smoothing or other finishing treatment, and this is usually accomplished by a machine known as a "Palmer" but in any event having a rotary drum (usually heated) around which the goods extends and by whose periphery it is finished by being held in close contact therewith for a time. It is known that although the tenter may have a constant speed the actual rate of delivery of the cloth to the Palmer is not constant, but varies, according to the conditions inherent in the cloth itself and brought into effect by the act of tentering, and that in consequence the cloth is likely to become transversely creased on the drum of the Palmer, which if heretofore rotated at variable speed was only so driven by a variable-speed drive manually controlled by an attendant. It has been proposed to regulate the speed of the Palmer automatically according to the speed of the cloth itself as by providing spaced guides (between the tenter and the Palmer) bridged by the cloth, and means, normally urged against the bridging portion of the cloth but movable by the cloth in the opposite direction, to control the shifter of means to drive the Palmer at variable speeds. It has also been proposed to utilize a cloth-expanding roller so that such roller would act to stretch the cloth transversely and thus restore it to the proper width and condition before it attains the Palmer if it should gather transversely and perhaps tend to crease lengthwise on leaving the tenter. But in the previous embodiment of these features there is room for improvement with a view to simplify the mechanism and attain greater efficiency, and it is the object of this invention to improve the previous mechanism in these respects.

In the drawing,

Fig. 1 is a side elevation of the Palmer and the adjacent end of the tenter equipped according to this invention; and

Fig. 2 is a plan of the cloth-expanding roller, partly in section.

The Palmer shown is of well known type, 1 being its frame; 2 the mentioned finishing drum journaled therein; 3 a belt whose por-

tion 3a tightly embraces the drum for nearly its whole circumference (i. e., except at the right) and the remaining portion 3b of which embraces the first portion, said belt extending around appropriately placed rollers 4 and also 55 around a smaller drum 5, one of said rollers being subject to movement by a screw device 6 for effecting tightening of the belt with respect to drum 2.

7 is the tenter delivering the cloth in the 60 direction of the arrow in Fig. 1; it may be of any well known construction.

The cloth *a* is received by the Palmer between the apron portion 3a and drum 2 and after passing around the drum it is led over 65 the topmost roller 4 shown to a rotary cooling mechanism 9 driven in any way, as by an endless chain 10 and gearing 22 itself driven as hereinafter stated, and thence to the take-up 11 driven by a belt-and-pulley friction 70 drive 12 from said mechanism. Of course it is not material, whether by these means or otherwise, how the cloth is disposed of after leaving the drum 2 of the Palmer.

The Palmer is driven by a variable drive 75 means, for example, a so-called Reeves drive which it is unnecessary to describe except as follows: In a frame 13 is fulcrumed at 14 a pair of levers or shifters 15 and journaled in the frame is the output shaft 17 of the transmission means, 16 being its input shaft driven at some constant speed by any prime mover, as an electric motor 18. On the shafts 16 and 17 are splined two pairs of reverse cone pulleys 19 and 20 surrounded by a belt 21. 80 When the shifters are moved on their fulcra one way or the other the pulleys of one pair are moved toward each other and the others allowed to move apart, whereby the belt climbs the cones of one pulley pair and descends those of the other, to afford variable speed of the output shaft. The latter shaft is connected by the mentioned gearing 22 with the drum 2.

At 23 and 24 are journaled rollers forming guides over which the cloth travels after leaving the tentering operation, guide 24 being the cloth-expanding roller.

At 26 is a roller-guide which bears on the cloth between the roller-guides 23 and 24 and

is journaled in a lever 27 whose fulcrum, shaft 28, is between its ends. Roller 26 is journaled in one arm of this lever and the other arm carries a counterweight 26a which 5 may be adjusted along the arm to such position that the guide will exert the proper pressure on the particular cloth being treated.

Shaft 28 is connected by a sprocket-and-chain connection 29 with the fulcrum shaft 10 30 of a lever 31 having oppositely projecting arms respectively connected by links 32 with the levers 15.

Thus, according as the portion of the cloth which bridges the guides 23 and 24 tends to 15 tauten or extend, the guide 26 rises or falls, acting through the train of parts connecting it with the shifters 15 to move the latter in opposite directions around their fulcras so that the variable transmission of which they 20 form a part respectively reduces or increases the speed of the drum. (Any other variable drive means may be resorted to). Moreover, if one of the three guides 23, 24 and 26 is a cloth-expanding roller it will act to expand 25 the cloth transversely while it is travelling. Thus, while transverse wrinkling of the cloth is prevented by controlling the speed of the drum 2 from the cloth itself, narrowing or lengthwise wrinkling of the cloth is prevented by the cloth-expanding roller.

In the mentioned previous construction the guide which formed the cloth-expanding roller was movable as a part of the speed-control means, wherefore its movement in this respect 30 made it uncertain and irregular in its cloth-expanding action. In the present construction this guide (24) occupies a fixed position between the guide (26), which now is the one movable with the speed-control means, and 35 the drum 2, so that its expanding action is uniform and occurs immediately before the cloth passes to the drum.

Rollers for expanding cloth transversely and travelling in tractive peripheral contact 40 with them are of divers well known kinds and any such may be used. Describing the roller shown (by way of example merely, and see Patent No. 1,799,603) by Fig. 2: An axial support 33 extends axially through a revolute cage comprising collars 34 journaled on the support at 33 (one near each end and one or more between) and these are rigidly connected by the parallel rods 35 arranged around said support. To the intermediate 45 collar (or collars) are affixed longitudinal slats 36. Confined by the rods to only sliding movement lengthwise thereof are other longitudinal slats 37 in two sets, with the set 36 between them and forming therewith 50 a cylindrical shell. These are engaged at 38a with the grooves of cams 38 (only one appearing) fixed on and thus in effect forming parts of the axial support 33. When the roller is in operation and is tractively engaged by the moving cloth each set of end

slats alternately moves toward and from the other end of the shell in progressive order under influence of the cams. In the present case, transverse stretching of the cloth being desired, it will be understood that the axial support is rotatively set so that its cams will move the particular end slats apart which are at any time engaged by the cloth.

While I have referred to a machine, as a Palmer, which by its drum smooths the cloth it is not material whether actual smoothing is effected; what is desired is to set the cloth by contact with the drum periphery, wherefore I refer to the Palmer as a machine for setting the cloth.

Having thus fully described my invention what I claim is:

1. Apparatus for expanding cloth comprising a tenter and a machine for setting the cloth delivered by the tenter having a revolute cloth-setting element around and in tractive engagement with which the thus-delivered cloth extends, said apparatus including spaced guides bridged by the cloth between said tenter and machine, means to drive said element at variable speed having a shifter movable in one direction to accelerate and in the opposite direction to retard the output speed of said means, a lever having a cloth-guide and normally urged to hold the cloth-guide against the bridging portion of the cloth, and means, connecting said lever and shifter, for moving the shifter in its first direction when said portion of the cloth slackens and in its second direction when said portion tautens.

2. Apparatus for expanding cloth comprising a tenter and a machine for setting the cloth delivered by the tenter having a revolute cloth-setting element around and in tractive engagement with which the thus-delivered cloth extends, said apparatus including spaced guides bridged by the cloth between said tenter and machine, means to drive said element at variable speed having a shifter movable in one direction to accelerate and in the opposite direction to retard the output speed of said means, a lever having a cloth guide to bear against the bridging portion of the cloth, means, adjustable along the lever, to cause it to yieldingly hold said cloth-guide under variable pressure against the bridging portion of the cloth, and means, connecting said lever and shifter, for moving the shifter in its first direction when said portion of the cloth slackens and in its second direction when said portion tautens.

3. Apparatus for expanding cloth comprising a tenter and a machine for setting the cloth delivered by the tenter having a revolute cloth-setting element around and in tractive engagement with which the thus-delivered cloth extends, said apparatus including spaced guides bridged by the cloth between said tenter and machine, means to drive

said element at variable speed having a shifter movable in one direction to accelerate and in the opposite direction to retard the output speed of said means, a lever having a cloth-guide and normally urged to hold the cloth-guide against the bridging portion of the cloth, and means connecting said lever and shifter, for moving the shifter in its first direction when said portion of the cloth slackens and in its second direction when said portion tautens, that one of the first two guides which is between said element and the third guide being a cloth-expanding roller.

15 In testimony whereof I affix my signature.
WILLIAM J. KOCH.
